[57] **CLAIM**

The ornamental design for a pan corner, as shown.

DESCRIPTION

FIG. 1 is a top perspective view of a pan corner showing my new design;
FIG. 2 is a top plan view, the bottom plan view being a mirror image thereof;
FIG. 3 is a front elevational view thereof;
FIG. 4 is an auxiliary elevational view taken along lines 4—4 of FIG. 2;
FIG. 5 is a right side elevational view thereof;
FIG. 6 is a sectional view taken along lines 6—6 of FIG. 2;
FIG. 7 is a top perspective view of a second embodiment of FIGS. 1-6;
FIG. 8 is a top plan view of the second embodiment; the bottom plan view being a mirror image thereof;
FIG. 9 is a front elevational view of the second embodiment;
FIG. 10 is an auxiliary elevational view of the second embodiment taken along lines 10—10 of FIG. 8;
FIG. 11 is a right side elevational view of the second embodiment; and,
FIG. 12 is a sectional view of the second embodiment taken along lines 12—12 of FIG. 8.
The broken lines shown in FIGS. 1-12 are for illustrative purposes only and form no part of the claimed design.
